UNITED STATES PATENT OFFICE.

FRITZ ALDENDORFF, OF ANTWERP, BELGIUM, ASSIGNOR, BY MESNE ASSIGNMENTS,
TO WESTERN ELECTRIC COMPANY, INCORPORATED, A CORPORATION OF NEW YORK.

SERVICE-METER CIRCUIT FOR TELEPHONE SYSTEMS.

1,175,579.

Specification of Letters Patent. Patented Mar. 14, 1916.

Application filed October 3, 1913. Serial No. 793,122.

To all whom it may concern:

Be it known that I, FRITZ ALDENDORFF, a subject of the King of Great Britain, residing at 59 Rue Wouw, Mortsel, Antwerp, 5 Belgium, have invented a Service-Meter Circuit for Telephone Systems, of which the following is a true, clear, concise, and exact description.

My invention relates to telephone systems 10 and has to do more particularly with service meter circuits for automatic telephone exchanges.

According to my invention the service meter circuits are so arranged that a call 15 made by a station is registered when the said station starts to make another call. The meter or register belonging to a calling station is prepared for registering the moment the station called by the calling station 20 responds. By arranging the system so that a call made by a station is registered when the station starts to make another call, certain advantages are obtained in cases where local connections—for instance between two subscribers in a certain city—are interrupted in 25 case one of the subscribers is wanted for a long distance connection to another town. In such cases a local subscriber, who has called and obtained connection with another 30 local subscriber can prevent the connection from being registered by his meter by continuing the conversation with a local subscriber, without having replaced his receiver on the switchhook, after the long distance 35 conversation is finished. For carrying out these ideas, devices are provided, by means of which an operator at a long distance exchange may cause the switches used for connecting two local stations to be restored, 40 further devices being provided which enable a station to reestablish a connection that has been disrupted by the intervention of the long distance exchange, and the meter circuits of the station being so arranged that 45 they are independent of any interference from the long distance exchange. In the case of a calling busy station being wanted for a long distance connection, the long distance operator actuates devices associated 50 with the first selector used by the calling subscriber for the local connection, these devices causing the first selector to be restored to its normal position, but not affecting the

line finder or distributing switch that has made connection between the calling subscriber and the first selector. In case a called busy subscriber is wanted for a long distance connection, the long distance operator disconnects the called busy subscriber from the calling subscriber, without restoring the switches used for the local connection. A signaling device is then connected to the calling end of the local connection, which may be associated with a phonograph or any kind of code signaling means that intimates to the calling subscriber that the called subscriber has been connected to a long distance line, and will be re-connected to him immediately the long distance conversation is finished. The circuits are so arranged that one and the same wire extending through the chain of selectors used for establishing a local connection serve for testing, metering and releasing.

The invention is shown in the accompanying drawings, in which—

Figure 1 shows a subscriber's station, a long distance switching device and a distributing switch; Fig. 2 shows the first selector; Fig. 3 illustrates the circuit of the second selector; Fig. 4 shows the circuits of the connector switch, and Fig. 5 shows the synchronous circuit changer used in connection with the selectors. In these only the circuits and parts essential to the invention are shown, all details unnecessary for a clear understanding of the essential features having been omitted.

In Fig. 1 a subscriber's station 100 and a long distance switching office 104¹ are represented as connected to a local exchange by lines 20, 21, and 31, 32, 33, 33' respectively. The subscribers, 100, are each connected to a distributing switch 101, having movable contacts 1, 2, 3, 4 capable of traveling over sets of fixed contacts, each set comprising four contacts 5, 6, 7, 8 connected to the wires 22, 23, 24, 25 which comprise a trunk leading to a selector 102, Fig. 2. Each line coming from the long distance office 104¹ 100 terminates in the local exchange in a selector 103, of which only the movable contacts 34, 35, 36, 400 and a few sets of fixed contacts are shown. Each subscriber's line 20, 21 is connected by wires 17, 18, 19, 401 to a set of 105 fixed contacts on selectors 103. Each sub-

scriber is provided with a meter 9 connected to devices belonging to the subscriber's line by wires 29, 30. Each subscriber's line may be connected to in the usual way by wires 5 26, 27, 28 and 391, 392 that lead to the contact banks of final selectors. Each distributing switch 101 comprises a line relay 38, a cut-off and line-extending relay 37, a driving magnet 39, and an off-normal 10 switch 40.

Fig. 2 represents a first selector. Since only such parts as are essential to the understanding of the invention are shown, the driving magnets of the selector 102 have 15 been omitted. The first selector is provided with a synchronous circuit changer 50 having a driving magnet 49 which steps around a movable contact arm 51 and the movable contact 52. At each step that the synchronous circuit changer 50 takes, the movable arms 51 and 52 travel a distance equal to that contained between the contacts 53 and 53' respectively, to the next contacts 54, 54'. The contact 53 is connected to the 20 negative pole of the battery. Contact 54 is at certain times connected to the negative pole of the battery through an armature contact 378 of a relay 371. The contact arm 52 is not long enough to make connection 25 with the contacts 53' to 54'. In traveling from the contacts 53' to 54' and from the contacts 54' to 55' the arm 52 brushes past pairs of contacts 56, 57 and 58, 59. In traveling from 30 53' to 54', the arm 52 momentarily connects the test brush 43 to a wire 60, which leads to the meter of a connected calling subscriber in a manner that will be described later. In traveling from 35 54' to 55' the arm 52 momentarily connects the negative pole of the battery to a wire 61 leading to the release magnet 46 of the selector 102, and under certain circumstances causes the selector 102 to be restored 40 to its normal position. The selector has a test relay 48, which controls contacts 62, 63, 64, 65, 66, 67. As long as the relay 48 is deenergized the contacts 62, 63, 64, 65, 67 are open, but when the relay is actuated, the 45 contacts 62, 63, 64, 65 and 67 are closed and contact 66 is opened. Normally relay 44 and a resistance 45 are connected through contacts 68, 69 of a relay 47 to the wires 22, 23 leading to a calling subscriber, and by the 50 relay 44 the calling subscriber controls the motor magnets or driving magnets of the first selector 102 and of the second selector 104, Fig. 3, and the other selectors 105, Fig. 4, used for establishing the connection. These motor magnet controlling circuits are 55 not shown, as they have nothing to do with the invention, and any known kinds of circuits may be used. The relay 47 is controlled from the long distance exchange 104 in the manner to be presently described. 60 All parts of the first selector 102 which have

not been mentioned will become clear in reading the description of the operation of the circuits given below.

In Fig. 3, 104 represents the essential features of a second selector, and in Fig. 4 the essential circuits of a final selector 105 are shown. The second selector 104 has a synchronous circuit changer comprising contact arms 73, 74 and a driving magnet 71. The operation of this circuit changer is similar to that described in connection with the first selector. The second selector has a test relay 75, which controls contacts 76, 77, 78, 79, 80, 81, 82 and 83. Normally contacts 76, 78 and 82 are closed, but upon the relay 75 being energized these contacts are opened, and contacts 77, 79, 80, 81 and 83 are closed. 85 and 86 indicate the driving magnets, and 84 the release magnet of the selector. The movable contacts of the selector are represented by 87, 88, 89, which travel over fixed contacts connected to trunks, each trunk being represented by the wires 90, 91, 92.

The final selector 105, Fig. 4, comprises a synchronous circuit changer 93 having contact arms 94, 95 and a driving magnet 357. The synchronous circuit changer is similar to that described in connection with the first selector. The final selector is provided with a meter control relay 98 that connects the negative pole of the battery to the pair of contacts 121, 120, whenever a completed call is to be registered. 97 represents the test relay of the final selector; 123 is a ringing control relay. 124 is a combined cut-off and line extending relay, which extends the line of the calling subscriber to that of the wanted subscriber, after the wanted subscriber has responded to a call, and at the same time cuts off the driving magnets 125, 126 of the final selector. The relays 127, 128 are connected to the wanted subscriber's line after this subscriber has responded to a call, and form the means by which the wanted subscriber can cause the switches to be restored to normal. The control of these relays is made independent of the calling subscriber by the condensers 129, 130 at the first selector, which prevent current flowing through these relays to the calling subscriber, while they still provide a path for the talking currents between a calling and a called subscriber.

In Fig. 5 a synchronous circuit changer of the kind used in connection with the selectors Figs. 2, 3, and 4 is shown. This instrument consists of a ratchet 150 that carries contact arms 151, 149 and is driven by a pawl 152 attached to a lever 153 that turns about a pivot 154, and has an armature 155 capable of being actuated by a magnet 156. On the driving magnet being energized, the armature 155 is attracted, and the pawl 152 is caused to engage with a new tooth, 157.

Attached to the lever 153 by a rod 158 is the piston 159 that reciprocates in a dashpot 160. On the armature 155 being attracted the valves 161, 162 of the piston 159 open so as to prevent the piston 159 from offering great resistance to the movement of the lever 153, so that when the electromagnet 156 is energized this lever acts promptly and allows the pawl 152 to drop quickly behind a new tooth 157 of the ratchet 150. Upon the subsequent deenergization of the magnet 156, the spring 163 which was stretched upon the energization of the magnet 156 exerts a pull on the lever 153 and causes the pawl 152 to move the ratchet 150 and the contact arms 151, 149 attached thereto, through an angle corresponding to the pitch of one tooth 157. This movement of the ratchet will bring the arm 149 from its normal contact 164 to the next contact 165, and the arm 151 will brush past the pair of contacts 166, 167. The movement of the ratchet caused by the spring 163 may be timed by the dashpot 160, so that the contacts 166, 167 may be closed for a certain period of time.

The meters 9, Fig. 1, used in connection with this system are of a special kind. The counting train is moved in the usual manner by ratchet 15, that is stepped forward by a pawl 14 attached to a lever 12, that turns upon a pivot 13. The lower end of the lever 12 extends to another lever 201 that has a catch 202. The upper end of the lever 12 is attracted so as to move the lever whenever a magnet 10 is energized. The lower end of the lever 12 then moves toward the right, and at its left side the catch 202 attached to the lever 201 rises so as to hold the arm 12 in the position into which it is moved by the attraction of the magnet 10. The lever 201 with the catch 202 can be pulled away from the lower end of lever 12 by a magnet 11. When this takes place the lever 12 is pulled toward the right by a spring 16, and then the pawl 14, which by the attraction of the lever 12 was caused to drop into a new tooth on the ratchet 15, drives this ratchet forward and causes a new call to be registered.

The operation of the system is as follows:—When the subscriber 100 raises his receiver from the hook in order to make the call, a current flows from the negative pole of the battery of the exchange through the right hand winding of the line relay 38, contact 300, line 20, subscriber's station 100, line 21, contact 301, left hand winding of line relay 38, back to the positive pole of the battery. The line relay 38 on attracting its armatures closes a circuit for the driving magnet 39, which may be traced from the negative pole of the battery through contact 302, 39, interrupter 303 to the positive pole of the battery. The pulsations now flowing

through the driving magnet 39 cause the contact arms 1, 2, 3, 4 to travel step by step from one set of fixed contacts 5, 6, 7, 8 to the next, until a free trunk 22, 23, 24, 25, Fig. 2, is found, when a current will flow through the test relay 37 from the negative pole of the battery through contact 304, winding 305, movable contact 3, fixed contact 8, wire 25, wire 306, contact 307, resistance 308, positive pole of the battery. Incidentally a circuit is also closed from the negative pole of the battery through 304, winding 305, wire 29, magnet 10 of the meter, to the positive pole of the battery. Magnet 10 is, however, so adjusted as to be energized only upon the direct application of the battery, and will not be energized by a current flowing through it through the winding 305. Test relay 37 attracts its armature and opens the contacts 300, 301 and 309 and closes the contacts 310, 311, 312, 313. By opening the contacts 300 and 301, the line relay 38 is deprived of current, so that the circuit of the driving magnet 39 is opened at contact 302 and the movable contacts 1, 2, 3, 4 are caused to stop. At contacts 310, 311 the calling subscriber's line 20, 21 is extended through 1, 6, 22 and through 2, 7, 23 to the first selector 102. By the closure of the contact 312 a part of the winding 305 of the test relay 37 is short circuited so as to cause a drop of potential on the test wire 25, which will prevent any other distributing switch 101 from connecting a calling subscriber to the same first selector 102. At the contacts 313 the negative pole of the battery is connected to the winding 305, so that the test relay 37 is not deprived of current by the deenergization of the line relay 38. It is to be noted that immediately the calling subscriber called, a circuit was closed by the line relay 38 through the armature contact 314 from the negative pole of the battery through 314, 30, magnet 11, to the positive pole of the battery. By this circuit the magnet 11 was energized until the line relay 38 was deprived of current through the distributing switch 101 having found a free trunk 22, 23, 24, 25. The electro-magnet 11 was then deenergized again. This energization of the electromagnet 11 simply causes the spring catch 202 to be pulled away for a short time from the lower end of the lever 12. By this function no appreciable effect is produced if the previous call made by the subscriber was an ineffective one.

After the called subscriber has been connected by the distributing switch 101 to a free selector 102, he proceeds to send selecting impulses through the relay 44 in a well-known manner. These impulses may be transmitted from the line relay 44 at the first selector switch to the operating magnets of the succeeding selector and connec-

41

tor switches as shown and described in the German patent to Siemens & Halske Akt.-Ges. No. 256,288, February 11, 1913. This series of selecting impulses have the effect 5 of causing the movable contacts 41, 42, 43 of the selector to hunt for a trunk leading to an idle selector 104. The moment an idle trunk 315, 316, 317 is found, the test relay 48 of the selector receives current over 10 the following path:—negative pole of the battery, contact 53, 51, 48, 66, 43, 317, resistance 318, positive pole of the battery. The test relay 48 then closes the contacts 62, 63, 64, 65 and 67 and opens the contact 15 66. By the closure of the contacts 64, 65 and 67 the driving magnet 49 of the synchronous circuit changer 50 is connected in parallel with the winding of the test relay 48. A drop of potential is hereby produced 20 on the test wire 317 and the busy condition of the trunk 315, 316, 317 established. The calling subscriber now sends another series of impulses through the relay 44, and this has the effect of sending impulses by any 25 known form of motor magnet controlling circuits, through the driving magnet 85 of the second selector 104 and through a change-over relay 86. This will cause the operation of the movable contacts 87, 88 30 and 89, which will hunt for an idle trunk line 90, 91, 92 leading to a final selector 105 in the group of subscribers in which the wanted line is contained. The moment a free trunk 90, 91 is reached the test relay 35 75 of the second selector is energized by a current flowing from the negative pole of the battery through contact arm 73, relay 75, contacts 82, 89, test wire 92, relay 96 to positive pole of the battery. The relay 96 40 is energized and closes contact 402 and this has the effect of energizing the driving magnet 357 of the synchronous circuit changer 93. The driving magnet 357 receives current from the positive pole of the battery 45 partly through the relay 96 and partly through the resistance 318, through test wires 317 and 92, contact 402, and from here the circuit continues through the magnet 357, contact arm 94, contact 403' to the negative pole of the battery. The relay 75 50 opens contacts 76, 78, 82, and closes the contacts 77, 79, 80, 81, and 83. This has the effect of extending the line wires 315, 316, 317 to the wires 90, 91, 92 respectively, and 55 of connecting the driving magnet 71 of the synchronous circuit changer 70 in parallel with the coils of the test relay 75. The potential of the test wire 92 is hereby lowered sufficiently to produce the busy condition of 60 the trunks 90, 91, 92. Having gained connection with an idle final selector 105, the calling subscriber sends two series of impulses to the controlling relay 44 in the usual manner, and these impulses are transferred 65 by any known system of circuits to the con-

trolling magnets 125, 126 of the final selector, so as to cause the movable contacts 320, 321 and 322 of the final selector to connect with the wanted subscriber's line.

After the contacts 320, 321, 322 have been 70 moved on to the contacts connected to the wanted subscriber's line, the circuit of the test relay 97 is closed, *e. g.* at 406, in the well known manner by the last change over impulse that ensues after the subscriber has 75 sent the last series of selecting impulses, and if the wanted line is idle a current will flow from the negative pole of the battery through contact 323, which is an off normal contact that is closed the moment the selector is moved out of its normal position through wire 324, test relay 97, contact arm 322, test wire 28, leading to the line of the wanted subscriber—(see Fig. 1), winding 323 of the test relay 37 of the wanted subscriber, contact 324, which is a contact on an off-normal switch 40 attached to the distributing switch 101 of the wanted subscriber, to the positive pole of the battery. The test relay 97 is then energized, and 80 closes the contacts 325, 326. By closing contact 325 a part of the test relay winding is short circuited, whereby the potential on the test wire 28 is lowered, and the busy condition of the wanted line established. 85 By the closure of the contact 326 the circuit of the ringing relay 123 is closed and this relay now causes the ringing machine to send out ringing current, which may be traced from the ringing machine 327 through contact 400 of the relay 123, contact 401, contact 381, 329, 321, 391, (Figs. 4 and 1), 396, 26, 20, wanted subscriber 100, 21, 27, 394, 392, 320, 330, 328, 402, ringing machine 327. When the called subscriber responds to the intermittent ringing current a ringing control relay 403 is energized, and closes the contacts 333, 334. By closing the contact 333 the relay 124 is energized by current flowing from the negative pole of the battery, contact 333, winding 124, positive pole of the battery. Relay 124 is energized and closes a locking circuit for itself through contacts 407 and 323. It also opens contacts 335, 328, 336, 115 331 and closes the contacts 337, 338, 339, 340. By opening the contacts 335 and 336 the driving electro-magnets 125, 126 that move the movable contacts 320, 321, 322, are cut off. At the contacts 328 and 331 120 the ringing current is cut off from the wanted line. By the closure of the contacts 337 and 339 the line 90 and 91 coming from the calling subscriber is extended to the line 329, 330 leading to the wanted subscriber. By the closure of the contacts 338 and 340 the relays 127, 128 and the battery 341 are bridged across the line leading to the wanted subscriber, and this subscriber now receives his battery supply through the 130

relays 127, 128. When the wanted subscriber responded and caused the relay 403 to be energized, the contact 334 was closed and the effect of this was to energize the 5 metering relay 98 by a current flowing from the negative pole of the battery contact 334, relay 98 to the positive pole of the battery. The relay 98 immediately closed a locking circuit for itself through the contact 342, and by closing a contact 343 it prepared the meter circuit for closure, this closure taking place when the connection is broken down. The system is so arranged that on the wanted subscriber replacing his 10 receiver the final selector and all the group selectors excepting the first group selector 102 are released. At the first group selector the replacing of the receiver by the wanted subscriber has only the effect of causing 15 the synchronous circuit changer 50 to take one step. In taking this one step the synchronous circuit changer at the first selector closes the meter circuit of the calling subscriber.

20 When the calling subscriber replaces his receiver he causes all the selectors used in establishing a connection to be restored to their normal positions. When the selectors are restored to their normal positions by 25 the calling subscriber replacing his receiver, the circuit changers 50, 70 and 93 at the group selectors and at the final selector step around in synchronism. In taking their first synchronous steps, the circuit changers 30 93 and 50 close the pairs of contacts 120, 121 and 56, 57 at the same instant, so that a circuit is closed, comprising the test wires extending through the chain of selectors used in establishing the connection and the calling 35 subscriber's meter. This circuit will be traced presently. After closing the meter circuit, the synchronous circuit changers when caused to move in response to the act of the calling subscriber in replacing his receiver, continue executing synchronous steps until each of them reaches and closes a pair 40 of contacts that control the release magnets of the various selectors. The release magnets are then energized and the selectors restored to their normal positions. If the 45 called subscriber is the first to replace his receiver all the synchronous circuit changers step around in the same way, as if the calling subscriber caused the release, but the 50 synchronous circuit changer of the first selector only takes one step in order to close the meter circuit, and then remains stationary until the calling subscriber also replaces his receiver. The synchronous circuit 55 changer of the first selector then steps forward and releases the first selector and the distributing switch belonging to the calling subscriber. The object in arranging the release circuits in this manner is to force the 60 calling subscriber to replace his receiver before he can establish a new connection. If the release circuits were so arranged as to cause the restoration of all the selectors the moment a called subscriber replaced his receiver, the calling subscriber could, without 65 replacing his receiver, cause the first selector that was used for the last connection or any other free first selector to which he is connected by his distributing switch to make a new connection with another subscriber. 70 For the satisfactory working of the meter system forming the subject of this invention it is, however, important to force a calling subscriber to energize his line relay each time he makes a fresh call. This is accomplished by so arranging the circuits as to keep the movable contacts of the first selector on the line 315, 316, 317 used for the last connection until the calling subscriber replaces his receiver. If the calling subscriber were now to attempt to make a new connection without replacing his receiver it is evident that he would obtain a wrong 75 connection. All that is necessary to prevent a subscriber from making two calls in succession without replacing his receiver is to inform him that such wrong connections will be obtained if he fails to comply with the regulations. If it be assumed that the wanted subscriber replaces his receiver first, 80 the restoration of the switches is initiated by the relays 127, 128 at the final selector. The relay 128 is slow-acting, so that it keeps its contact 351 closed for a short time after the contact 352 is closed by the de-energization of the relay 127. This results in a current flowing from the negative pole of the battery through 352, 351, releasing relay 353, 85 to the positive pole of the battery. The relay 353 closes a locking circuit for itself through the contact 354, and by closing the contact 355 connects an interrupter to the test wire 92. This interrupter intermittently connects the negative pole of the battery to the test wire 92, and thus short circuits the magnets 357, 71 and 49 on the synchronous circuit changers. These are thus 90 deprived of current, and then enable the springs 163, Fig. 5 to drive forward their pawls so that their contact arms take a step 95 forward.

The test relays 48 and 75 are short-circuited at the same time as the driving magnets 357, 71 and 49 of the synchronous circuit changers but these are arranged to let 100 their armatures drop back slowly so that the relays will be re-energized by currents flowing from the positive pole of the battery through the relay 96 and resistance 318, the moment the short-circuit is taken off the test 105 wire 92 by the interrupter 356. Thus the short-circuits produced by the interrupter 356 only result in steps being taken by the circuit changers 93, 70 and 50, but do not 110 cause the relays 48, 75 and 96 to let their 115

120 125 130

armatures drop back. Between the first and second applications of the negative pole of the battery to the test wire 92, the arms 95, 74 and 52 of the synchronous circuit changers, each brush past a pair of contacts, the synchronous circuit changer 93 closing the contacts 120, 121 and the circuit changer 50 closing the contacts 56 and 57. The negative pole of the battery is then directly applied to the metering wire 60 at the first selector, and a current flows from the negative pole of the battery through contact 343, at the final selector, contacts 121, 120, busy test wire 92, movable contact 89, contact 80, wire 317, movable contact 43, wire 358, contacts 57, 56, metering wire 60, wire 306, 25, contact 8, movable contact 3, wire 29, magnet 10 of the meter 9. It will be noted that the direct applications of the negative pole of the battery to the test wires 92, 317 by the interrupter 356 do not result in applications of the negative pole to the metering wire 60, because at the moments that the interrupter 356 applies the battery, the contacts 56 and 57 at the first selector are open, and these contacts can only be closed at a moment in which the interrupter 356 disconnects the negative pole of the battery from the test wires 92 and 317. When the prepared meter circuit is closed in the manner described above, the magnet 10 pulls over the lever 12 so as to cause the pawl 14 to engage a new tooth of the meter ratchet 15, and to cause the lower end of the lever 12 to move behind a catch 202. The meter will now register conversation as soon as the line relay of the calling subscriber is energized, and causes the current to flow through the magnet 11. This takes place after the calling subscriber has replaced his receiver, and then takes his receiver off the hook again in order to make a new call.

The releasing operation has been traced up to the point where the synchronous circuit changers 93, 70 and 50 had stepped their arms forward one step, due to the negative pole of the battery having been applied to the test wire 92. By the further applications of the negative pole to the test wire 92 through the interrupter 356, only the synchronous circuit changers 93 and 70 are affected so as to continue stepping forward their contact arms. The synchronous circuit changer 50 does not continue its forward movement because it is not reenergized after it has taken its first step, the negative pole of the battery being disconnected from the contact 54, so that the circuits of the driving magnet 49 and of the test relay 48 are definitely opened until the calling subscriber replaces his receiver, as will be presently described. Upon the second application of the negative pole of the battery to the test wire 92 by the interrupter 356, the driving magnets of the synchronous circuit

changers 93 and 70 are deprived of current a second time, so that each of them moves its contact arms another step. In taking this second step the circuit changers each close a pair of contacts at the same moment, the 70 circuit changer 93 closing the contacts 360, 361, and the circuit changer 70 closing the contacts 362, 363. By the closure of the contacts 361, 360, the release magnet 364 of the final selector is energized by a current flowing from the negative pole of the battery through 360, 361, 364 to the positive pole. The closure of the contacts 362, 363, results in the release magnet 84 of the second selector being energized by a current from 80 battery through 363, 362, 84 to the positive pole of the battery.

When the calling subscriber replaces his receiver the relay 44 definitely lets its armature drop back, so that a slow acting relay 370 is deenergized, and closes a circuit for the release relay 371, which may be traced from the negative pole of the battery through contact 372, 456, wire 420, relay 371, off-normal switch 365, to the positive 90 pole of the battery. The release relay 371 is energized and immediately closes a locking circuit for itself through contacts 374 and 365. By closing the contacts 378 and 379 the release relay closes a circuit for the 95 driving magnet 49 of the synchronous circuit changer 50. This circuit may be traced from the negative pole of the battery through 378, contact 54, contact arm 51, which is now resting upon contact 54, magnet 49, contact 379, resistance 421, positive pole of the battery. The magnet 49 is short-circuited immediately after by the negative pole being applied to the wire 377 through the interrupter 376, so that the circuit 105 changer takes a second step forward. In executing this step the movable contact 52 brushes past the contacts 58, 59 and closes the circuit of the release magnet 46, which may be traced from the negative pole of the 110 battery through 59, 58, 61, 46 to the positive pole of the battery. The first selector will then be restored to its normal position. At the moment the release magnet 46 is energized this magnet opens the contact 307, 115 thus opening the circuit of the test relay 37 at the distributing switch. This relay releases its armatures, and closes the contact 309. This results in a new circuit being established for the driving magnet 39 of the 120 distributing switch—from the negative pole through 309, contact 380, 301, driving magnet 39, interrupter 303, positive pole. The driving magnet then propels the arms 1, 2, 3 and 4 in a forward direction, until the 125 distributing switch reaches its normal position, when the circuit of the driving magnet 39 will be opened at the contact 380. The synchronous circuit changers 50, 70, and 93 are so constructed that after having taken 130

two steps they are ready to produce another cycle of circuit changes of the same kind and sequence as in the previous cycle.

It was assumed above that the releasing of the switches was started by the wanted subscriber. It will now be assumed that the calling subscriber first replaces his receiver. The effect of this is to deenergize the relay 44 in a manner already described, so that the slow-acting relay 370 also deenergizes, and a circuit is closed from the negative pole through the contacts 372, 456, wire 420 and relay 371 to the positive pole. The relay 371 closes a locking circuit for itself through the contacts 374 and 365. By the contact 375, the releasing relay 371 connects the interrupter 376 to the wire 377, and as the test relay 48 still has its armature attracted, the interrupter 376 will also be connected through the contacts 64 and 65 to the test wire 317. It will also be connected through the contacts 64 and 67 to the test relay 48. On each application of the negative pole of the battery to the test wire 317, the test relays 48, 75 and the driving magnets 49, 71 and 357 of the circuit changers will be short-circuited. As the test relays allow their armatures to retract rather slowly they will keep their armatures energized in the intervals between the short-circuitings produced by the interrupter 376, but the driving magnets 49, 71 and 357 will release their armatures and cause the movable arms of the circuit changers to step forward. As the circuits of the test relay 48 and of the driving magnet 49 at the first selector are now kept closed at the contact 54 through the armature 378 of the release relay 371, the synchronous circuit changer 50 will participate in the synchronous movements of the circuit changers 70 and 93, not only in taking its first step, but also in taking its second step. In taking their first steps the circuit changers 93 and 50 close the meter circuit through the pairs of contacts 120, 121 and 56, 57 in a manner already described. In taking their second steps the synchronous circuit changers 50, 70 and 93 close the release circuits of their respective release magnets 46, 84 and 364 in the manner described above. The circuit of the test relay 37 of the distributing switch 101 is also opened at the contact 307, so that the distributing switch is also caused to return to its normal position.

The events which take place in case a busy subscriber is wanted for a long distance conversation will now be described.

If the calling subscriber is wanted, all the selectors are released by the long distance operator, except the distributing switch 101 of the calling subscriber. The long distance operator selects the line by means of a selector 103, and finding the wanted subscriber busy he closes a contact 380, which has

the effect of energizing a relay 47 in the first selector, by a current flowing from the negative pole of the battery through 47, 24, 5, 4, 19, 34, 31, 380 to the positive pole. Relay 47 is kept energized; it opens the contacts 68 and 69, at the same time closing contacts 381, 382, 383 and 384. By the closure of the contact 382 the release relay 371 is energized by a current flowing from the negative pole of the battery through 382, 371, 365, to the positive pole. The release relay 371 then closes its contacts 374, 375, 378 and 379, and causes the selectors 102, 104, 105 to be released in a manner already described. The restoration of the distributing switch 101 to its normal position is prevented by the contact 307 of the release magnet 46 being short-circuited by the contact 381. A conversation may now be carried on over the wires 32 and 33 and over the wires 17, 18 leading from the long distance exchange to the local office. When the long distance conversation is finished, the calling subscriber, without replacing his receiver, sets up the local connection again through the switches 102, 104, 105, and as his line relay 38 is not energized again in making a new connection with the subscriber from whom he was previously disconnected, the previous local call will not be registered until the calling subscriber has finished the desired local conversation and reenergizes his line relay 38 in making another call. When the long distance exchange disconnects, relay 47 is deenergized and the relay 44 is reconnected to the trunk 22, 23, its armature being kept attracted by the current flowing from the battery 450 to the calling subscriber. Should the calling subscriber decide to abandon the connection which he had previously made to another local subscriber, he will replace his receiver and open his line loop, thus deenergizing the relay 44. The armature of the relay 44, by opening the contact 454 deenergizes the relay 370. This slow-acting relay then allows its armature to retract so as to open the contact 455 and close contact 456. The opening of the contact 455 causes the deenergization of a relay 452, which is also slow acting. Before the relay 452 has time to open its armature contact, a circuit is closed from the negative pole of the battery through contacts 372, 456, 457, wire 458, contact 459 (which has a normal contact that is kept closed by the synchronous circuit changer whenever this is in its normal position, but which is opened whenever the circuit changer is in any other position), wire 453, release magnet 46, positive pole of the battery. The energization of the release magnet 46 causes the opening of the contact 307 and the deenergization of the test relay 37 at the distributing switch. The deenergization of the test relay of the distributing switch results in the distributing switch being stepped 130

into its normal position in the manner already described. If the wanted subscriber is disconnected from the calling subscriber by the long distance office, the calling subscriber waits until the long distance conversation is finished, and is then immediately reconnected to the wanted subscriber. As all the subscribers in the exchange are provided with similar apparatus it may be assumed for the moment that the station 100 is that of the wanted subscriber, and that another similar station is connected to it through selectors similar to 102, 104, 105. The long distance exchange 104 connects to the wanted subscriber through a selector 103, and on finding the wanted station busy closes the contact 380. In this case the closing of the contact 380 does not affect any relay 47 in a first selector, because the arms 1, 2, 3, 4 of the distributing switch are in a normal position and the only effect produced by closing the contact 380 is to energize a relay 390. The relay 390 opens the contacts 393, 394 and closes contacts 395, 396, thus disconnecting the wires 391, 392 coming from the calling subscriber from the wires 26, 27, leading to the called subscriber, and connects the wires 391, 392 to a tone-giving device 397. The device 397 causes a sound to be propagated over the wires 391, 392 to the calling subscriber, thus notifying him of the disconnection, due to a long distance conversation. The tone-giving device 397 does not permanently open the circuit of the relays 127, 128 at the final selector, but allows intermittent current to flow through these relays so that the final selector release circuit is not closed. The calling subscriber then waits until the long distance conversation is finished, which will generally be in the space of two or three minutes, when the contact 380 at the long distance exchange is opened, and the relay 390 deenergized so as to reestablish the connection between the calling local subscriber and the wanted local subscriber over the wires 391, 392 and 26, 27. At the finish of the conversation the calling and called local subscribers replace their receivers and cause the selectors to be restored to their normal positions in the manner already described above. Any subsequent removal of the receivers from the switchhooks at the local stations will cause the energization of the line relay 38, and the closure of the circuit through the electromagnet 11 of the meter 9 of the particular calling station, so that if a successful call had previously been made by the calling station, this previous successful call will be recorded by the meter 9.

Although I have referred in my above specification to the exchanges for local and long distance connections as "local exchange" and "long distance exchange," I desire it to be understood that I do not wish

to be limited by these specific terms, for the functions described in connection with the long distance exchange might just as well be performed by some other kind of special exchange.

Obviously in the practice of my invention many alterations and modifications may be made, both in the circuit arrangement and the mechanical structure of the device without departing from the spirit and scope of the invention; thus, for example, the several batteries shown herein as separate and distinct, may be one and the same. Other like modifications may be made. I, therefore, do not wish to be limited to the specific matter disclosed, but aim to cover by the terms of the appended claims all such alterations and modifications.

I claim:

1. In a telephone system, the combination with a plurality of calling and called lines, of selector and connector switches adapted to automatically interconnect said lines, conversation recorders, preparatory circuits extending through said switches for controlling the preliminary action of said recorders, said preparatory circuits being controlled by said called lines, and supplementary circuits for controlling the final action of said recorders to effect registration, said supplementary circuits being controlled by said calling lines.

2. In a telephone system the combination with a plurality of calling and called lines, of selector and connector switches adapted to automatically interconnect said lines, conversation counters, relays at said connector switches, circuits extended to said called lines by said switches and including said relays, preparatory circuits controlling a preliminary counting action of said counters and controlled by said relays, line relays associated with said calling lines, and supplementary circuits for controlling the final action of said counters to effect registration, said supplementary circuits being closed by said line relays.

3. In a telephone system, the combination with a plurality of calling and called lines, of electro-magnetically controlled selectors and connectors adapted for interconnecting said lines, conversation counters, relays at said connectors, circuits extended to said called lines by said connectors and including said relays, preparatory circuits controlling a preliminary counting action of the said counters and controlled by said relays, line relays associated with said calling lines, and supplementary circuits for controlling the final action of the said counters to effect registration, said supplementary circuits being closed by said line relays.

4. In a telephone system, in combination, a plurality of lines, selector and connector switches adapted to automatically inter-

connect said lines, conversation counters, a propelling device in each of said counters, electromagnetic means associated with the connector for controlling the initial movement of said propelling device, and line relays associated with the calling line to finally operate said propelling device and effect registration.

5. In a telephone system, in combination, 10 a plurality of lines, selector and connector switches adapted to interconnect said lines, conversation counters, means associated with said lines for causing the operation of said switches, electromagnetic means associated with said connectors to impart an initial operation to said conversation counters after the called subscriber answers, and line relays associated with said calling lines for subsequently completing the action of 20 said counters to effect registration.

6. In a telephone system, in combination, a plurality of lines, selector and connector switches adapted to automatically interconnect said lines, conversation recorders, 25 line relays associated with said lines, preparatory circuits controlling the initial action of said conversation recorders, said preparatory circuits extending through said switches and supplementary circuits for controlling the final action of said recorders to effect registration, said supplementary circuits being closed by said line relays.

7. In a telephone system, in combination, 35 a plurality of calling and called lines, conversation recorders, electro-magnetically controlled switches for associating one of said calling lines with one of said called lines, normally opened contacts in said switches for maintaining an interruption 40 between a calling line and a called line that has been associated therewith, a relay associated with one of said switches that is energized in a circuit including the called line, electro-magnetically controlled device for closing said normally opened contacts, said device being controlled by said relay, a recorder control relay, preparatory circuits for controlling a preliminary recording 45 action of said recorder and closed by said recorder control relay, a line relay associated with the said calling line, and supplementary circuits for controlling the final action of said recorders to effect registration, said supplementary circuits being closed by said line relay.

8. In a telephone system, in combination, 50 a plurality of calling and called lines, conversation recorders, electro-magnetically controlled selectors and connectors for associating a said calling line with a called line, normally opened contacts in said connectors for maintaining an interruption between a calling line and a called line after they have been associated with each other by said 55 selectors and said connectors, a relay asso-

ciated with each connector that is energized in a circuit including the said called line, a second relay associated with said connector for closing the said normally opened contacts and controlled by a said first relay, a recorder control relay, preparatory circuits controlling the preliminary recording action of the said recorders and closed by said recorder control relays, line relays associated with said calling lines, and supplementary circuits controlling the final action of said recorders to effect registration, said supplementary circuits being closed by said line relays.

9. In a telephone system, in combination, 80 a plurality of calling and called lines, conversation recorders, electro-magnetically controlled selectors and connectors, talking contacts in said selectors and connectors for associating a said calling line with a said 85 called line, normally opened contacts at said connectors for maintaining an interruption between a calling line and a called line after they have been associated with each other by some of said selectors and one of said 90 connectors, a relay associated with each of said connectors that is energized by a current flowing over a called line, a second relay at a said connector for closing the said normally opened contacts and controlled by 95 a said first relay, test contacts in said selectors and connectors, a recorder control relay, preparatory circuits for controlling the preliminary recording action of said recorders and closed by said recorder control relays, said preparatory circuits including a 100 said test contact, a line relay associated with said calling lines, and supplementary circuits for controlling the final action of said recorders to effect registration, said supplementary circuits being closed by said line relays.

10. In a telephone system, in combination, 105 a plurality of calling and called lines, electro-magnetically controlled selectors and connectors for associating a said calling line with a said called line, synchronously acting circuit changers at said selectors and connectors, conversation counters, relays at said connectors, circuits extended to said called lines by said connectors and including said 110 relays, preparatory circuits for controlling the preliminary counting action of said counters and controlled by said relays, said preparatory circuits including parts of the 115 said synchronously acting circuit changers, line relays associated with said calling lines, and supplementary circuits controlling the final action of said counters to effect registration, said supplementary circuits being 120 closed by said line relays.

11. In a telephone system, in combination, 125 a plurality of calling and called lines, electro-magnetically controlled selectors and connectors, trunks extending between said selec- 130

tors and connectors, said trunks each containing talking wires and a test wire, said selectors and connectors having talking contacts for extending a calling line to a called line, said 5 selectors having also test contacts for connecting to test wires of said trunks, restoring magnets for restoring said selectors and connectors to the normal positions, conversation counters, relays at said connectors, 10 circuits extended to said called lines by said connectors and including said relays, preparatory circuits for controlling the preliminary counting action of said counters and controlled by said relays, said preparatory 15 circuits and the circuits of the said restoring magnets being closed through the said test wires, line relays associated with said calling lines, and supplementary circuits for controlling the final action of said counters 20 to effect registration, said supplementary circuits being closed by said line relays.

12. In a telephone system, in combination, a plurality of calling and called lines, electro-magnetically controlled switches, one of 25 said switches being used in establishing a connection between a calling line and a called line, a restoring magnet for restoring such switch, restoring circuit for controlling said magnet, said restoring circuit being controlled only by the calling line, a conversation 30 counter associated with said calling line, a preparatory circuit controlling the preliminary action of said counter, said preparatory circuit being controlled by the 35 called line, and a supplementary circuit controlling the final action of said counter to effect registration, said supplementary circuit being controlled by the calling line relay.

40 13. In a telephone system, in combination, a plurality of calling and called lines, electro-magnetically controlled selectors and connectors, one of said selectors in co-operation with one of said connectors being 45 adapted to associate a calling line with a called line, a restoring magnet for restoring the said selector, said restoring magnet being controlled only by the said calling line, a connector restoring magnet for the said 50 connector, said connector restoring magnet being under the control of the calling line and of the called line, a conversation counter associated with the calling line, a preparatory circuit controlling the preliminary action of said counter, said preparatory circuit being controlled by said called line, and a supplementary circuit controlling the final action of said counter to effect registration, said supplementary circuit being controlled 55 by the calling line relay.

60 14. In a telephone system, the combination with subscribers' lines, of selector and connector switches for establishing connection between said lines, conversation recorders, means to effect an initial operation of said 65

recorders when the calling subscriber disconnects, and means to finally operate said recorder to register the call when the calling subscriber initiates the next call.

15. In a telephone system, in combination, 70 a local exchange, another exchange, a plurality of called and calling lines connected to the local exchange, electro-magnetically controlled switches at the local exchange, one of said switches being adapted for associating 75 a calling line with a called line, a restoring magnet for restoring said switch, a restoring circuit for controlling said magnet, said restoring circuit being controlled by the calling and called line, and by the said other exchange, a conversation counter associated 80 with said calling line, a preparatory circuit controlling the preliminary action of said counter, said preparatory circuit being controlled by the called line, and a supplementary circuit controlling the final action of 85 said counter, said supplementary circuit being controlled by the calling line.

16. In a telephone system, the combination 90 with subscribers' lines, of selector and connector switches for establishing connection between said lines, conversation recorders, means operable to give said recorders an initial actuation during the dependency of the call, and means to finally actuate said recorder to register the connection when the calling subscriber initiates the next call.

17. In a telephone system the combination 95 with subscribers' lines, of selector and connector switches for establishing connection 100 between said lines, conversation recorders, a line relay associated with each line, means controlled by the calling subscriber to initially operate said recorder after the called subscriber responds, said recorder being 105 finally operated to register the connection upon the actuation of the line relay when the calling subscriber initiates the next call.

18. In a telephone system, in combination, 110 a local exchange, another exchange, a plurality of calling and called lines connected to the local exchange, electro-magnetically controlled switches at the local exchange, one of said switches being used in establishing a connection between a calling line and a called line, a restoring magnet for restoring said switch, an electro-magnetic device associated with the called line, said device being controlled by the said other exchange 115 and being adapted to disconnect the calling line from the called line, a restoring circuit being controlled only by the calling line, a conversation counter associated with the calling line, a preparatory circuit controlling the preliminary action of said counter, said preparatory circuit being controlled by the called line, and a supplementary circuit controlling the final action of said counter, said supplementary circuit being controlled by 120 the calling line.

19. In a telephone system, in combination, a local exchange, another exchange, a plurality of calling and called lines connected to the local exchange, electro-magnetically controlled switches at the local exchange, one of said switches being used in establishing a connection between a calling line and a called line, a restoring magnet for restoring said switch, a signaling device, an electro-
10 magnetic device associated with a called line, said device being controlled by the said other exchange and being adapted to disconnect the calling line from the called line and to connect the said signaling device to the
15 calling line, a restoring circuit for controlling said restoring magnet, said restoring

circuit being controlled only by the calling line, a conversation counter associated with the calling line, a preparatory circuit controlling the preliminary action of said counter, said preparatory circuit being controlled by the called line, and a supplementary circuit controlling the final action of said counter, said supplementary circuit being controlled by the calling line. 20
25

In witness whereof, I hereunto subscribe my name this 12th day of September A. D. 1913.

FRITZ ALDENDORFF.
